PALLET

Ernest Cardwell Holdredge, Decatur, Ga., and Larry Lee Marifjeren, Scotch Plains, N.J. assignors to Allastics, Inc., Norcross, Ga.

Filed June 1, 1970, Ser. No. 23,213

Term of patent 14 years

Int. Cl. D12—14
U.S. Cl. D14—3

FIG. 1

FIG. 2

FIG. 1 is a top, front and one side perspective view of a pallet showing our new design; and

FIG. 2 is a bottom, rear and other side perspective view of the pallet.

The characteristic feature of the present invention resides in the design of the top surface of the pallet which is best shown in FIG. 1 of the drawing.

I claim:

The ornamental design for a pallet, substantially as shown and described.
